UNITED STATES PATENT OFFICE.

CHARLES T. GROSJEAN, OF NEW YORK, N. Y., ASSIGNOR TO TIFFANY & CO.,
OF SAME PLACE.

DESIGN FOR A HAND-MIRROR FRAME.

SPECIFICATION forming part of Design No. 17,421, dated June 28, 1887.

Application filed March 18, 1887. Serial No. 231,450. Term of patent 7 years.

To all whom it may concern:

Be it known that I, CHARLES T. GROSJEAN, a citizen of the United States, and a resident of New York city, in the county and State of New York, have invented and produced a new and original Design for Hand-Mirror Frames, of which the following is a specification, reference being had to the accompanying drawings, forming part thereof.

Figure 1 is a top or plan view of my newly designed hand mirror frame. Fig. 2 is a side view of the same, and Fig. 3 is an end view of the same. Fig. 4 shows the design applied to a different kind of hand-mirror frame. Figs. 1^a, 1^b, 1^c, 1^d are sectional views on the lines *a a*, *b b*, *c c*, and *d d* of Fig. 1, respectively.

My design has special reference to the body part of the hand-mirror frame, as distinguished from the handle. Various forms of handles, therefore, can be used without departing from my invention.

The design consists in the shape or outline of the body of the mirror-frame, and also in the shape or outline of the recess for receiving the glass, as they are shown in a horizontal or plan view of the mirror-frame. Hitherto the outlines of such mirror-frames have been made substantially oval or elliptical in character, or else substantially square or rectangular.

The character and effect of the present design are entirely new and different from anything hitherto produced in the art.

The present design consists in the outline of the mirror and the outline of the recess for the glass, as shown in Figs. 1, 4, and 5. The side lines of the mirror and of the recess for the glass curve but slightly at their middle portions and during the greater part of their length; but at their ends the curve is deepened so as to meet the curving ends of the top and bottom lines. The top lines of the mirror and the recess are also curved very slightly and delicately, and the bottom lines are formed substantially as the top lines except so far as the bottom line of the mirror may be modified to meet the lines of the handle.

This design gives a peculiar and subtle richness and fullness to the body of the mirror, such as cannot be obtained by any variety of oval or elliptical forms, and yet avoids the stiffness and abruptness of any rectangular form.

What I claim as new, and desire to secure by Letters Patent, is—

The design for hand-mirror frames, substantially as shown and described, consisting of the outline of the body combined with the outline of the recess for the glass, both outlines having their sides and top lines curved but slightly, with sharp curves at the corners, and the bottom lines curved like the top lines.

CHARLES T. GROSJEAN.
